CLAIM

The ornamental design for an article of clothing as shown and described.

DESCRIPTION

FIG. 1 is a front perspective view of an article of clothing showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view.

The broken line showing of the person is for environmental purpose only and forms no part of the claimed design.
